AUTOMATIC STOPPING MECHANISM FOR CORNER-STAYING MACHINES.

1,084,631.

Specification of Letters Patent. Patented Jan. 20, 1914.

Application filed January 15, 1913. Serial No. 742,265.

To all whom it may concern:

Be it known that we, ERNEST L. HAZEL and RICHARD HOLBECHE, subjects of the King of Great Britain, residing at Birmingham, England, have invented new and useful Improvements in Automatic Stopping Mechanism for Corner-Staying Machines, of which the following is a specification.

Our present invention relates to safety automatic stopping mechanism for corner staying machines of the type designed to attach corner-stays to the corners of paper or cardboard boxes, and the object of the invention is to provide means for automatically stopping the machine in case the hand or a finger of the operator should happen to be in the path of movement of the corner-staying die during its descent toward the anvil with which the die coöperates.

It is a well known fact that the operation of these corner-staying machines, which are now quite generally used by box manufacturers, is attended with frequent accidents to the operators occasioned by the operator carelessly, or from lack of experience allowing his or her hand, or a finger thereof, to come between the die and anvil, during the movement of the die toward the anvil in the act of applying the stay to the corner of a box and this results in a mashed or maimed finger.

Some attempts have been made to obviate this danger in the present known types of machines, as by providing movable finger-guards that are designed to sweep across the face of the anvil in advance of the movement of the die and brush or move away any obstruction that may be in the path of movement of the die, but these finger-guards have not been entirely satisfactory since they do not always accomplish the object for which they are intended.

According to the present invention we provide simple and extremely sensitive means which coöperate with the stay-applying devices, and the driving means for the machine for automatically and instantly stopping the descent of the die in case there should be an obstruction of any kind in the path of movement of said die.

Briefly and generally stated the invention comprises movable members positioned to sweep over the diverging faces of the anvil in advance of and during the descent of the

die, and means actuated by said movable members and coöperating with the driving mechanism of the machine for automatically stopping the same before the die reaches the anvil.

The mechanism is so designed that it may be readily applied as an attachment to known types of machines and without altering the design thereof.

In order to enable others to understand, make and use our said invention, we will now proceed to describe the same in detail, reference being had for this purpose to the accompanying drawings, wherein:

Figure 1 is a front elevation of a portion of a corner-staying machine having our improvements applied thereto. Fig. 2 is a side elevation of the same, the driving pulley and its clutch being shown in section. Fig. 3 is a horizontal section of the friction clutch taken on the line 3—3 of Fig. 1, looking in the direction of the arrow. Fig. 4 is a side elevation of the driving pulley and its ball-clutch.

Referring to the accompanying drawings wherein like reference characters indicate the same parts throughout the several views, the numeral 1, designates the head portion of a well known type of corner-staying machine, said head having parallel guides 2, between which is mounted a vertically reciprocating member 3, carrying a die 4 at its lower end, which die coöperates with a stationary anvil 5 having diverging walls, as is usual in machines of this type. The member 3 with its die 4 is reciprocated by means of a shaft 6, on which is loosely mounted a pulley 7 that is driven continuously, a ball-clutch of known construction being interposed between the hub 8 of the pulley and a collar 9, fixed to the shaft 6. The ball-clutch embodies as a part of its construction, a disk 10 that normally rotates with the pulley, said disk having a laterally projecting lug 12 with which a treadle-operated gag 13 is arranged to coöperate, said gag operating when the treadle is actuated to move in the path of movement of and be engaged by the lug on the clutch disk in order to shift the position of the same and cause the pulley to run free and stop the rotation of its shaft, and consequently reciprocation of the die 4 toward its anvil 5.

As the parts just described are of known

construction and constitute no part of the present invention, except as they operate in combination with other parts presently to be described, further description thereof is deemed unnecessary, provided it is understood that so long as the gag or other stop is out of the path of movement of the laterally projecting lug 12, of the clutch-disk, the pulley will be locked to its shaft so as to 5 rotate the latter and reciprocate the die 4, but as soon as the lug on the clutch disk comes into contact with a gag or other stop thrust in the path of movement thereof, the pulley will immediately be disengaged from 10 the shaft so as to run free thereon which results in instantly stopping the downward movement of the die before it reaches the anvil, the stopping point of the die relatively to the anvil depending upon the position of the lug when it engages its stop or 15 gag. The lug 12 and its coöperating gag 13 are so positioned relative to the shaft 3 that one complete revolution of the pulley with its clutch disk will effect a single reciprocation of the die, or in other words, will move 20 the die down into contact with its anvil and bring it back again to the starting position. It will be apparent therefore, if a second gag is interposed in the path of movement 25 of the lug 12, at a point slightly beyond the initial starting position, as indicated in Fig. 4, the machine will be stopped before the die reaches its anvil. We have taken advantage 30 of this operation in applying our improvements to a known type of corner staying machine having the form of clutch referred to. It will be apparent, however, that our improvements may be applied to machines having some other type of clutch or driving 35 means than that shown, without departing 40 from the spirit of the invention, the showing here made being only by way of example.

We will now proceed to describe our improvements in detail, which as before stated 45 are shown as associated with a known type of machine and which when broadly stated, embody means operable through the interposition of an obstruction between the corner-staying die and its associated anvil for 50 throwing the die-operating means out of action and stopping the descent of the die.

The reference numerals 14, designate a pair of movable guards, consisting in the instance shown of curved or arched plates, one 55 such guard located on each side of the path of movement of the die 4, and each pivoted at its outer end, as at 15, to a bracket 16, attached to the head 1, of the machine and having its inner end arranged to sweep over 60 the adjacent converging face of the anvil 5, during each downward movement of the die 3.

Secured to a bracket 17 projecting outward from the head 1 of the machine is a 65 stud or pin 18, upon which is loosely mount-

ed for oscillation, a sleeve 19 carrying a pinion 20 at one end, which pinion is in mesh with a rack 21, secured to the outer face of the reciprocating die-carrier 3, the said rack operating to impart an oscillating movement 70 to the sleeve 19, during each reciprocation of the die carrier 3. Mounted upon the sleeve 19 for movement therewith and also for movement independently thereof, is an oscillatory arm 22, the said arm during the 75 normal operation of the machine, being caused to partake of the oscillating movements of the sleeve, by means of a very sensitive friction clutch consisting of a pair of fiber disks 23 and 24 one located on each side 80 of the arm 22, and engaging said sides frictionally. The disk 23 is forced into frictional contact with one side of the arm by means of a coiled spring 25, acting upon a washer 26, the tension of the spring, and consequently the frictional resistance between the parts, being adjusted as desired by means of a nut 27 threaded upon the sleeve and acting against the spring, said nut when set for proper adjustment of the 85 spring being held against turning movement by means of a lock-nut 28, also threaded upon the sleeve 19.

The movable guard-members 14 are each 90 connected to one end of the arm 22, by means 95 of the connecting rods 29, so that with each reciprocation of the die 4, the free ends of the guard-members are caused to sweep back and forth over the diverging walls of the anvil in advance of the die, this operation 100 resulting by reason of the friction clutch connection between the lever 22 and sleeve 19, and occurring so long as there is no obstruction in the path of movement of the said guard-members, but in case there should 105 be any such obstruction present, it will be engaged by one or the other or both of the guard members 14, whereupon the arm 22 will be held against movement, the sleeve 19 turning relatively thereto, this action also 110 being permitted by reason of the friction clutch connection between the sleeve and arm.

Pivottally connected to the outer end of the arm 22 is a vertically extending link 30, 115 said link being pivottally connected at its upper end to a lever 31 pivoted at 32 to a bracket 33 secured to the head 1 of the machine frame. The lever 31 is connected at its outer end by a link 34 to one arm 35 of a bell-crank lever, which bell-crank lever is pivoted at 36 to a bracket 37 also secured to the head of the machine frame. The other arm 38 of the bell-crank lever has a link connection 39, with a horizontally sliding gag or locking dog 40, the latter reciprocating freely in a guide 41 secured to the machine frame. During normal operation of the machine the free end of the gag or locking dog 40 is reciprocated back and 120 125 130

forth into and out of the path of movement of, but not in contact with, the laterally projecting lug carried by the clutch disk 10 during each reciprocation of the die 4, this 5 movement of the gag or dog 40 being brought about by reason of the rack and pinion connection between the die carrier 3 and sleeve 19, the friction clutch connection between the sleeve 19, and arm 22 and the lever 10 and link connections with the said gag or locking dog.

The operation of the machine will be clearly understood from the foregoing description taken in connection with the following brief statement.

Normally the gag 13 is in engagement with the lug 12 of the clutch disk 10 as shown in Fig. 4, and the pulley 7 then runs free upon the shaft 6, the operating parts 20 of the machine being idle. When it is desired to start the machine the gag 13, by means of a suitable treadle mechanism not shown, is shifted out of engagement with the lug 12, and this causes the clutch disk 25 10 to bring about a locking engagement between the pulley 7 and its shaft 6, the shaft being then rotated to impart reciprocatory movements to the die 4 to cause the same to move back and forth toward and from and 30 in contact with its anvil 5 in order that the corner stays may be applied to the box corners as said corners are positioned over the anvil, it being understood, of course, that a strip of stay material is fed over the corners of the box as they are presented to the 35 anvil. During each successive downward movement of the die the guards 14 sweep across the corners of the box in advance of the downward movement of the die, and so 40 long as there is no obstruction of any kind in the path of movement of the guards the free end of the gag 40 will, with each reciprocation of the die, be thrust into the path of movement of the lug 12, which now 45 rotates with the drive shaft 6, but will be withdrawn out of said path before the lug 12 can make contact therewith and the machine will run continuously in this manner. If, however, an obstruction of any kind, 50 such for instance as a finger of the operator, should chance to be in the path of movement of either of the guards 14 during the descent of the die, such obstruction will instantly stop further downward movement of 55 the guards, and through their connections with the gag 40 including the friction clutch connection of the arm 22 with its oscillating means, which friction clutch prevents relative movement between the arm 60 and sleeve, will maintain said gag in the path of movement of the lug 12, so as to be engaged thereby. When so engaged the clutch disk 10 will be shifted to disengage the pulley 7 from its driving connection 65 with the shaft 6 to cause the same to run

free from the shaft, whereupon the machine will be instantly stopped, the die 4 coming to a state of rest before it reaches its anvil 5, this being due to the fact that the gag 40 is so positioned relative to the starting position of the lug 12 that it will be engaged thereby, provided the gag has not been withdrawn, before the die has made a full stroke downward.

While we have shown our improvements 75 as applied to a corner staying machine, we do not wish to be understood as limiting ourselves to the application of the improvements to this particular type of machine, as obviously with slight modifications, they 80 may be associated with other types of machines employing a reciprocating die or other member.

What we claim is:—

1. In a corner staying machine, the combination with a reciprocating die and a co-operating anvil, clutch controlled driving means for said die, guards adapted to sweep across the face of said anvil during the reciprocation of said die in advance of the 85 downward movement thereof, means for actuating the clutch to disconnect said die from its driving means, and connections between said guards and the clutch actuator for rendering the latter inoperative when 90 the guards pass across the anvil.

2. In a corner staying machine, the combination with a reciprocating die, and a co-operating anvil, clutch controlled driving means for said die, guards adapted to 100 sweep across the face of said anvil during the reciprocation of said die in advance of the downward movement thereof, means operated by the movement of the die for imparting motion to said guards, a frictional 105 slip connection forming a part of said means, means for actuating the clutch to disconnect said die from its driving means, and connections between said frictional slip connection and the clutch actuator for rendering the latter inoperative when the guards 110 are passed across the anvil, and holding said actuator in operative position when the guards encounter an obstruction.

3. In a corner-staying machine, the combination with a reciprocating die and co-operating anvil having diverging faces, of means for imparting a reciprocating movement to the die, movable members actuated by the die for sweeping across said diverging faces of the anvil, and means actuated through the interposition of an obstruction in the path of movement of said movable members, or either of them, for throwing said die moving means out of action.

4. In a corner-staying machine, the combination with a reciprocating die and co-operating anvil, of a driving shaft for imparting reciprocating movements to the die, clutch-controlled driving means for shaft.

a movable guard pivotally mounted to sweep over the face of the anvil during the reciprocating movements of the die, a rocking arm for swinging said guard, means carried by the die for operating said arm, and means actuated by said rocking arm for throwing the clutch-controlled driving means out of operation to stop the machine.

5. The combination with a reciprocating die and coöperating anvil, of a driving shaft for imparting reciprocatory movements to the die, clutch-controlled driving means for the shaft, a gag coöperatively associated with said clutch-controlled driving means for throwing the latter out of operation, movable guards adapted to sweep over the faces of the anvil during the reciprocating movements of the die, and connections between said movable guards and said gag 10 for operating the latter, said connections including a frictional slip connection.

6. In a corner staying machine, the combination with a reciprocating die and a coöperating anvil having diverging faces, of means for imparting reciprocatory movements to the die, a pair of pivoted guards positioned to sweep back and forth over the said diverging faces of the anvil, means operated by the reciprocatory movements of the die for imparting the said back and forth movements to said guards, and means actuated by the guards when either or both encounter an obstruction for stopping the operation of the machine.

35. 7. In a corner staying machine, the combination with a reciprocating die carrier carrying a die and a coöperating anvil, of a drive shaft for imparting reciprocatory movements to the die carrier and its die, a pulley freely mounted on the drive shaft, a clutch-disk for locking the pulley to the shaft, a gag coöperatively associated with said clutch-disk, a guard movable back and forth across the face of the anvil in advance of the die, and means operated by the die carrier for positively actuating the movable guard in both directions, and for reciprocating the said gag, said means including a frictional slip connection.

50. 8. The combination with a reciprocating die, of a driving shaft for imparting reciprocatory movements to the die, clutch-controlled driving means for the shaft, a gag coöperatively associated with said clutch-controlled driving means for throwing the latter out of operation, means mounted on the die and operating during the reciprocating movements thereof for actuating the gag, a guard movable in advance 55 of the die and moved positively by said means on the die, and connections between

the guard and gag for operating the latter through the interposition of an obstruction in the path of movement of the guard, said connections including a frictional slip connection. 65

9. In a corner staying machine the combination with a reciprocating die-carrier carrying a die, clutch-controlled driving means for the die-carrier, a pair of pivoted guards positioned for movement in advance of the die, an oscillating arm pivoted on a fixed support, means actuated by the die-carrier for oscillating the arm, a frictional slip connection between the arm and its actuating 70 means, a gag coöperatively associated with the said clutch-controlled driving means, and connections between said gag and oscillating arm.

10. In a corner staying machine, the combination with a die-carrier and its die, a driving shaft for imparting reciprocatory movements to the die-carrier and its die, clutch-controlled driving means for the shaft, pivotally mounted guards positioned 85 for movement in advance of the die, an oscillating arm having independent connections with said guards, means operated by the die-carrier for oscillating the arm, said means including a frictional connection, a gag coöperatively associated with the clutch-controlled driving means, and operative connections between said gag and oscillating arm.

11. In a corner-staying machine the combination with a reciprocating die-carrier and its die, of a shaft for imparting reciprocatory movements to the die-carrier, clutch-controlled driving means for the shaft, a pair of pivoted guards positioned for movement in advance of the die, a fixed stud, a sleeve free to oscillate on said stud, a rack and pinion connection between the die-carrier and sleeve for rotating the latter, an arm frictionally supported upon the sleeve, 100 connections between the guards and one end of the arm, a gag coöperatively associated with the clutch-controlled driving means, and operative connections between said gag and the other end of the said arm. 105
